(57) **CLAIM**

The ornamental design for a “closure cap,” as shown and described.

DESCRIPTION

FIG. 1 is a perspective view showing our new design;

FIG. 2 is a first side elevational view;

FIG. 3 is a second side elevational view;

FIG. 4 is a top plan view; and,

FIG. 5 is a bottom plan view.

The broken lines in the drawings depict probable environment only and form no part of the claimed design.
